Specification for Design.

Patented May 11, 1920.

Application filed December 6, 1919. Serial No. 343,128. Term of patent 14 years.

To all whom it may concern:

Be it known that I, JAMES E. BARNEY, a citizen of the United States, residing at New York, in the county of New York and State of New York, have invented a certain new, original, and ornamental Design for a Rubber Sole-Pad for Boots and Shoes, of which the following is a specification, reference being had to the accompanying drawing, forming part thereof.

Figure 1 is a bottom plan view and Fig. 2 a side elevation of a rubber sole pad showing my new design.

I claim:

The ornamental design for a rubber sole pad for boots and shoes, as shown.

In testimony whereof I have affixed my signature.

JAMES E. BARNEY.
